UNITED STATES PATENT OFFICE.

EDWIN EVANS, OF LYNN, MASSACHUSETTS.

DESIGN FOR BODY OF A GAS-BURNER.

Specification forming part of Design No. **7,492**, dated June 16, 1874; application filed March 11, 1874.
[Term of Patent 7 years.]

To all whom it may concern:

Be it known that I, EDWIN EVANS, of Lynn, of the county of Essex and State of Massachusetts, have invented a new and original Design for the Body of a Gas-Burner; and do hereby declare the same to be fully described in the following specification and represented in the accompanying drawing, which exhibits a front or side elevation of a gas-burner body having the design or external configuration.

The main part of the body A has the form of two single bells, *a* *b*, conjoined at their bases, the lower bell terminating in a cylindrical neck, *c*, and the upper in a spherical or spheroidal head, *d*, united to the upper bell by a tapering or bell-shaped neck, *e*, all being as represented. The body is circular in sections at right angles to its longer axis.

This burner-body does not include what is termed the "tip," which is a separate matter.

Between the bell-shaped parts *a* *b* there is no cylinder, they, at their junction, terminating in a narrow fillet or bead, as shown.

In an application for a patent made by me, and now pending before the Patent Office, I have represented a burner analogous in shape to this. The subject of such application, however, was not the design, configuration, or external shape, but related to the mechanical construction of the burner.

I claim as my invention or production—

The said ornamental design or configuration for a gas-burner body, it being composed of the two single bells *a* *b*, their junction-fillet, the cylindrical neck *c*, and spherical or spheroidal head *d*, with its tapering or bell-shaped neck *e*, all as represented.

Witnesses: EDWIN EVANS.
